UNITED STATES PATENT OFFICE.

JAMES H. BOYE, OF CHICAGO, ILLINOIS.

CURTAIN-HANGER.

1,301,368.

Specification of Letters Patent. Patented Apr. 22, 1919.

Application filed February 21, 1917. Serial No. 149,994.

To all whom it may concern:

Be it known that I, JAMES H. BOYE, a citizen of the United States, residing at Chicago, in the county of Cook and State of Illinois, have invented certain new and useful Improvements in Curtain-Hangers, of which the following is a specification.

This invention relates to devices for suspending curtains and draperies in front of windows or in other locations, and has reference principally to that type of curtain supports or hangers wherein the curtain rod is an extensible telescoping member, so as to fit different widths of curtain, is applied to the curtain by being passed through a hem in the upper edge of the latter, and is removably supported by brackets.

The curtain hanger of my present invention embodies certain structural features of a curtain hanger forming the subject-matter of Letters Patent No. 1,229,874, granted to my assignee June 12, 1917, and is in the nature of an improvement upon the construction disclosed and claimed in said patent, designed to increase the capacity and utility of said construction. Among the specific objects sought by the present invention are, to provide a construction which shall be readily interchangeable to support either a curtain and a full overdrape or a curtain and side drapes; to provide a construction applicable to double or bay windows wherein the curtain rod or rods for each window can be put up or removed entirely independently of, and without disturbing, the hangings of the other window or windows; to provide an improved construction of detachable rods for a side drape supported at one end by one of the end or intermediate brackets and at its other end by the main curtain rod; to provide an improved construction of end brackets adapted to support a pair of curtain rods arranged one in front of the other; and to provide an improved construction of intermediate or T-brackets likewise adapted to support a pair of curtain rods arranged one in front of the other. Other objects and advantages of the invention will be readily apprehended by those skilled in the art from the following description taken in connection with the accompanying drawings, wherein—

Figure 1 is a perspective elevation of my improved curtain hanger shown as applied to a double window, and adapted to carry a curtain and an overdrape;

Fig. 2 is a partial top plan view, somewhat enlarged, of Fig. 1;

Fig. 3 is an enlarged central vertical section through the T-bracket which constitutes the intermediate supporting member;

Fig. 4 is a horizontal section on the line 4—4 of Fig. 3;

Fig. 5 is a perspective inner side elevation of the head portion of the T-bracket, showing one end of a curtain-rod detachably mounted therein;

Figs. 6 and 7 are views similar to Figs. 1 and 2, respectively, but showing the hanger as adapted to carry a curtain and side drapes;

Fig. 8 is an enlarged sectional view of one of the end brackets on the line 8—8 of Fig. 7;

Fig. 9 is a sectional detail of one of the end brackets on the line 9—9 of Fig. 8; and

Fig. 10 is a perspective elevation from the inner side of one of the short detachable rod sections adapted to carry a side drape.

Referring to the drawings, Figs. 1 and 2 illustrate the invention as arranged to carry a curtain and a full overdrape; while Figs. 6, 7 and 10 show the same as adapted to carry a curtain and side drapes. Both arrangements are shown as applied to double windows; and the detail views, Figs. 3, 4, 5, 8 and 9, show details of structure that are common to both arrangements.

11 designates as an entirety each of a pair of double end-brackets, 12 designates as an entirety an intermediate double T-bracket, and 13 designates as an entirety each of a pair of extensible main curtain rods disposed between and supported by the intermediate and end-brackets respectively.

The double end-bracket 11, specifically described, comprises a pair of overlapping base plates 14 and 15 united by a rivet 16 and provided with registering holes for attaching screws 17; outwardly divergent curved arms 18 and 19 springing from the base plates 14 and 15 respectively and located in the same horizontal plane, and substantially flat parallel head portions 20 and 21, the upper and lower margins of which have inwardly turned lips 22 (Fig. 8) that form receiving sockets for the outer ends of the rods hereinafter described.

The double intermediate T-bracket 12, specifically described, comprises a base plate 23 provided with holes for attaching screws 24, a forwardly projecting main stem or

arm 25, a branch stem 26 attached to the main stem 25 as by inwardly turned clips 27 embracing notched edges 28 of the main stem (Fig. 4), and substantially flat parallel head portions 29 and 30 carried by the stems 25 and 26, respectively, the upper and lower margins of said head portions having at both ends inwardly turned lips 31 (Fig. 5) that form receiving sockets for the inner 10 proximate ends of the curtain rods. Each of the heads 29 and 30 is further formed with a central internal protuberance 29' and 30', respectively, conveniently formed by indenting the metal at that point, which 15 protuberance co-operates with a wire loop connector member carried by the end of a rod to stiffen and render more secure the engagement of the connector member with the socket of the head.

20 Each of the two rear rods 13 which carry the main curtain comprises a pair of hollow rod sections 32 and 33 of flattened or oval form in cross-section, the latter telescoping in the former, as shown, to produce a rod 25 having a considerable range of adjustment as to length.

25 In the embodiment of the invention shown in Figs. 1 and 2 extensible rods 13', each comprising telescoping sections 32', 33', and 30 in all respects identical and interchangeable with the rods 13, are employed to carry a full overdrapery. In the embodiment shown in Figs. 6 and 7 the rods 13' are replaced by short rod sections 34, two for each main 35 curtain rod 13, which are employed to carry side drapes.

30 The outer or bracket-engaging ends of the rods 13, 13' and 34 are all equipped with identical devices for detachably mounting the said ends of the rods in the receiving sockets of the brackets, such device consisting of a generally U-shaped elastic wire loop 35, the legs of which are clamped securely in the end of the rod by downwardly mashed portions 36 (Figs. 4 and 8) of the infolded sides of the rods. The loops are slightly wider than the sockets which they engage, so that they are transversely compressed as they are forced into the sockets, 45 and preferably the loops and sockets are formed with co-operating edge indentations as indicated in Fig. 9, for detachably locking them together. This construction permits a slight vertical play of the end of the 50 rod in and relatively to its supporting bracket which obviates the necessity of a high degree of accuracy in the mounting of the brackets so as to have their receiving sockets exactly in line. It also permits a 55 sufficient degree of horizontal flexing of the end of the rod relatively to its supporting bracket to adapt the construction to bay windows where the individual sections of the window are not in the same plane but 60 at an angle to each other. This described 65

construction of socket and wire loop connector member is not specifically claimed herein, however, as it forms in part the subject-matter of my prior patent above identified.

70 As the wire loop is forced into the socket, the closed end of the loop rides up onto the protuberance 29' and 30' which puts a flexing strain on the loop in a direction transverse to its plane, and increases both the 75 rigidity and frictional grip of the connection, making it more secure. This last mentioned improvement, which obviously may be employed in either or both the intermediate and end brackets, constitutes a valuable 80 feature of the present invention.

85 The short rod section 34, which carries the side drape in the construction of Figs. 6, 7 and 10, is equipped at its inner end with a device for detachably supporting said 90 inner end on one of the sections of the main curtain rod 13; this device, in the preferred embodiment herein shown, consisting simply of an elbow-shaped member 37 (Fig. 10) 95 having a substantially flat stem or shank 38 that is securely clamped between the infolded marginal portions and the solid wall of the rod 34, and a curved body portion 39, the free end of which carries a pair of 100 spring clips 40 that can be readily snapped on and off the main curtain-rod 13. It will thus be seen that by a simple interchange of the outer or front rods 13' and 34, the full drape structure may be converted into a side drape structure, and vice versa.

105 It will also be noted that the described construction renders each section of the double or bay window hanger structure entirely independent of the other section or sections. Each can be assembled and taken down without disturbing the other, and each section can be organized for either full or side drapes independently of the arrangement of the other section or sections. The 110 construction is simple, durable, economical to manufacture, and easy to manipulate, and is adaptable to practically any and all situations where a curtain hanger is required. The structure shown and described may obviously be modified in detail without departing from the substance of the invention 115 as defined in the appended claims.

I claim:

1. In a curtain hanger for double windows, the combination with end brackets and an intermediate T-bracket, of independent curtain rods between said T-bracket and end brackets, respectively, each of said rods being removably engaged with and supported by one of said end brackets and one arm of 125 said T-bracket.

2. In a curtain hanger for double windows, the combination with end brackets each having a receiving socket at its free end, of an intermediate T-bracket having a 130

- receiving socket on each side thereof, the sockets of the end-bracket and T-bracket on each side of the latter opening toward each other, and independent curtain rods between 5 each formed with sockets adapted to detachably engage with the proximate ends of two curtain rods.
5. In a curtain hanger, a T-bracket adapted to support the proximate ends of two pairs of curtain rods and comprising an attaching base, a forwardly projecting main stem, a branch stem attached to and supported by said main stem, and front and rear head portions each formed with sockets on its opposite sides adapted to detachably engage with the proximate ends of two curtain rods. 60
10. In a curtain hanger for double windows, the combination with end-brackets each having front and rear receiving sockets at its free end, of an intermediate T-bracket 65 having front and rear receiving sockets on each side thereof, the sockets of the end-bracket and T-bracket on each side of the latter opening toward each other, and independent pairs of curtain rods between said 15 T-bracket and end-brackets, respectively, each rod of each pair being capable of lengthwise expansion and contraction and adapted to detachably engage with a receiving socket of said T-bracket and a receiving 20 socket of one of said end-brackets under an expanding movement of said rod.
15. In a curtain hanger, the combination with a supporting bracket having front and rear receiving sockets at its free end, of a curtain rod having one end detachably engaged with the rear socket of said bracket, a support for the other end of said rod, and a rod section adapted to carry a side drape 25 detachably engaged at one end with the front socket of said bracket and detachably connected at its other end to said curtain rod. 30
20. In a curtain hanger, the combination with a supporting bracket having front and rear receiving sockets at its free end, of a curtain rod having one end detachably engaged with the rear socket of said bracket, a support for the other end of said rod, and a rod section adapted to carry a side drape 35 detachably engaged at one end with the front socket of said bracket and detachably connected at its other end to said curtain rod.
25. In a curtain hanger, the combination with a supporting bracket having front and rear receiving sockets at its free end, of a curtain rod having one end detachably engaged with the rear socket of said bracket, a support for the other end of said rod, and a rod section adapted to carry a side drape 40 detachably engaged at one end with the front socket of said bracket and provided at its other end with a spring clip detachably engaging said curtain rod.
30. In a curtain hanger, a T-bracket adapted to support the proximate ends of two pairs of curtain rods and comprising an attaching base, a forwardly projecting bifurcated stem, and front and rear head portions 55 each formed with sockets adapted to detachably engage with the proximate ends of two curtain rods.
35. In a curtain hanger, a supporting bracket formed with a substantially flat receiving socket having a protuberance on the inner surface of a side wall thereof, in combination with a curtain rod having at one end a projecting spring wire loop connector 60 adapted to slidably engage with said socket and at its free end bear against and be laterally flexed by said protuberance.
40. In a curtain hanger, a T-bracket the head portion whereof forms a pair of oppositely disposed alined substantially flat receiving sockets, and is provided with a central protuberance on the inner surface of a side wall thereof, in combination with a pair 65 of curtain rods having at their proximate ends projecting spring wire loop connectors adapted to slidably engage with said sockets and at their free ends bear against and be laterally flexed by said protuberance. 70
45. In a curtain hanger, an end-bracket 75 for a pair of rods, comprising overlapping base-plates provided with registering holes for attaching screws, and outwardly divergent curved arms terminating at their free ends in parallel receiving sockets for the 80 ends of the rods.
50. In a curtain hanger, an end-bracket 85 for a pair of rods, comprising overlapping base-plates fastened together and provided with registering holes for attaching screws, and outwardly divergent curved arms located in a common plane and terminating at their free ends in front and rear parallel receiving sockets for the ends of the rods. 90
55. In a curtain hanger, an end-bracket 95 for a pair of rods, comprising overlapping base-plates fastened together and provided with registering holes for attaching screws, and outwardly divergent curved arms located in a common plane and terminating at their free ends in front and rear parallel receiving sockets for the ends of the rods. 100

JAMES H. BOYE.
